(57) **CLAIM**

The ornamental design for a liquid fertilizer maker, as shown and described.

DESCRIPTION

FIG. 1 is a perspective view of the liquid fertilizer maker from the front and right.

FIG. 2 is an elevation of the right side thereof.

FIG. 3 is an elevation of the left side thereof.

FIG. 4 is an alternate perspective view of the liquid fertilizer maker from the front and right showing the plunger in an up position; and,

FIG. 5 is an alternate perspective view of the liquid fertilizer maker from the front and right showing a removable watering can in a partially removed position.

The product facilitates the “brewing” or “steeping” of green kitchen or garden waste material in water to produce a liquid fertilizer than can be watered onto plants to promote their growth.
